UNITED STATES PATENT OFFICE

ALBERT HOSSFELD, OF WINONA, MINNESOTA.

FRICTION GRIP FOR DRILLING MACHINES

Application filed April 20, 1932. Serial No. 606,372.

My present invention relates to a friction grip for drilling machines of the type disclosed and broadly claimed in my pending United States application for Letters Patent filed December 4, 1931 under Serial Number 578,883.

It has been found that friction grips for the above use, when made entirely of iron, soon crystallize and break due to the terrific force and speed at which the drill is operated. It has also been found that an all metallic grip will shift bodily on the rod or shank of a drill during the reciprocatory movement of the drill, due to the weight and inertia of the grip, thus producing rapid wear between the metal to metal contact of the parts and the almost constant friction between said parts will produce a high degree of heat. This wear on the rod of a drill soon changes the shape of the rod so that it does not have a constant diameter, and hence, the grip, will not engage the same at all points with the same pressure. Furthermore, this wear between a drill rod and the grip and the resulting heat will soon roughen the contacting surfaces of the rod and the grip to such an extent that they will "freeze" and thereby interfere with the feeding of the drill through the grip.

The object of the present invention is to provide a simple and highly efficient friction grip of lighter weight than iron so that the weight and inertia of the grip will not shift said grip on a drill rod during the reciprocatory movement of the drill thus eliminating excessive wear and heat and preventing the grip from crystallizing and breaking.

To the above end, generally stated, the invention consists of the novel devices and combinations of devices hereinafter described and defined in the claims.

In the accompanying drawing, which illustrates the invention, like characters indicate like parts throughout the several views.

Referring to the drawing:

Fig. 1 is a fragmentary perspective view of a drilling machine having the improved friction grip embodied therein;

Fig. 2 is a side elevation of the improved

friction grip and a fragment of the drill rod or shank, on an enlarged scale;

Fig. 3 is a view principally in section taken on the line 3—3 of Fig. 2;

Fig. 4 is a fragmentary detail view, with some parts sectioned on the line 4—4 of Fig. 2 and with the respective bolt removed;

Fig. 5 is a perspective view of one of the blocks looking at the inner face thereof; and

Fig. 6 is a perspective view of one of the resilient members removed from the grip.

The drilling machine fragmentarily illustrated in the drawing is fully shown, described and broadly claimed in the application heretofore identified.

Of the parts of the drilling machine shown, it is important to note the drill 7, the main frame 8, the carriage 9, the tilting frame 10, the connecting rods 11, for reciprocating the carriage 9 on the tilting frame 10, the compression propelling spring 12, and the compression buffer spring 13. The drill 7 includes a body 14 in the form of a long round steel rod and a cutter 15 on one end of said body. This drill 7 is mounted on the carriage 9 for compound reciprocating and rotary movements. A pair of laterally spaced cross-tie plates 16 which form a part of the tilting frame 10 support a striker plate 17. The two spring 12 and 13, which encircle the drill body 14, engage opposite ends of the carriage 9 as bases of resistance and their inner ends are axially spaced.

The improved friction grip 18, which is the subject matter of this application, is mounted on the drill body 14 between the springs 12 and 13, normally rests on the buffer spring 13 and supports the drill therefrom with the grip 18 above the striker plate 17 and normally out of contact therewith. The propelling spring 12 is secured to a rotatable bearing 19 on the carriage 9 and oscillated, during the reciprocatory movement of the carriage 9, by connections 20 from said bearing to the tilting frame 10.

The operation of the improved drilling machine may be briefly described as follows, to wit: The upward movement of the carriage 9 gives the drill 7 a powerful throw upward through the medium of the buffer spring 13

acting on the grip 18 and the force of this upward throw, which causes the drill 7 to travel at a faster speed than the carriage 9, is caught and absorbed by the propelling spring 12 which is compressed and placed under tension under the action of the grip 18 thereon.

Downward movement of the carriage 9 gives the drill 7 a powerful downward throw that is accelerated by the expansion of the compressed propelling spring 12 which causes the drill 7 to attain a high velocity. At or practically at the end of the downward stroke of the drill 7, the grip 18 is brought to a stop by its engagement with the striker plate 17 and as the drill 7 advances into the rock it drives itself through the grip 18 by the force of its momentum. The feeding of the drill 7 through the grip 18 takes place at a series of almost imperceptible steps of movement.

For the purpose of this case it is not thought necessary to describe in detail the rotary movement imparted to the drill 7 by the action of the propelling spring 12 on the grip 18.

Referring now in detail to the friction grip 18 the same includes a pair of laterally spaced blocks 21 of wood or other non-metallic material that is lighter than iron. These blocks 21 have in their opposing faces half seats 22. At the outer face of each block 21 is a metallic face plate 23 and interposed between each block 21 and its face plate 23 is a relatively thick resilient member 24 of rubber or other suitable resilient material. A pair of bolts 25 equipped with nuts 26 extend through aligned holes in the blocks 21, resilient members 24, and face plates 23. These bolts 25 are located on diametrically opposite sides of the drill body 14 and relatively close thereto. The heads of the bolts 25, the nuts 26 and the face plates 23 have ball and socket bearing surfaces 27.

By reference to Fig. 3 it will be noted that the holes in the blocks 21 are of such diameter as to leave clearance between said bolts and blocks and permit slight angular movement of the bolts 25 with respect to the blocks 21. The object of this angular movement of the bolts 25 and the provision of the ball and socket surfaces 27 is to permit slight relative shifting movements of the blocks 21 in case said blocks do not engage the striker plate 17 evenly or at the same time. It will be noted that the face plates 23 are of such width as to leave the top and bottom of said blocks exposed and prevent the face plates 23 from coming into direct contact with the striker plate 17. The inner faces of the plates 23 are slightly dished to hold the resilient members 24 thereon but at the same time permit said members to float during compression thereof.

Interposed between the blocks 21 and substantially surrounding each bolt 25 is a resil-

ient blocks 28, preferably of sponge rubber, mounted in recessed seats 29 in the oposing faces of the blocks 21. Each resilient block 28 is notched at 30 to leave a passageway for the respective bolt 25. These resilient blocks 28 are held under compression by the blocks 21 and the object thereof is to separate the blocks 21 when the nuts 26 are turned on the bolts 25 to reduce the pressure of the blocks 21 on the drill body 14. The bolts 25 clamp the blocks 21 onto the drill body 14 with sufficient friction to hold the grip 18 against bodily movement on said drill body under the action of the propelling spring 12 and buffer spring 13.

Obviously the compressed resilient members 24 will always keep the blocks 21 pressed onto the drill body 14 and compensate for any slight variation of the diameter of said body. This frictional contact between the grip 18 and the drill body 14 is sufficient to overcome the inertia and the weight of the grip 18 and prevent the grip 18 from shifting longitudinally on the drill body 14 during the reciprocatory movement of the drill 7. It will thus be seen that the grip 18 will not move on the drill body 14 except as said grip is stopped by the striker plate 17 during the operative stroke of the drill 7 and at which time the drill body 14 moves through the stopped grip by its momentum and at which time the cutter 15 performs its work.

It often happens that a step of rotary movement of the drill 7 will position its cutter 15 on a high spot on the stone being cut, and hence, the grip 18 will not engage the striker plate 17, during this stroke of the drill 7, and hence, there will be no movement of the drill body 14 through the grip 18. Neither will the force produced by the stopping of the drill 7, by its contact with the work, cause the grip 18 to move on the drill body 14 and thus prevent wear between the contacting parts.

From the above description it is evident that the drill body 7 and grip 18 have no relative movement except the step by step movement of the drill body 14 through the grip 18 produced by the movement of the drill body 14 through the grip 18 at the time said grip is stopped by the striker plate 17, thus eliminating all excessive wear which at present takes place between a metallic grip and drill body and produced by the almost continuous shifting of the grip on the drill body caused by the weight and inertia of the grip at the time the reciprocating carriage reverses its direction of travel. By forming the blocks 21 of wood or other non-metallic metal wear between said blocks and the drill body 14 will be very slight.

What I claim is:

1. A friction grip including a pair of laterally spaced blocks having cooperating half seats in their opposing faces, a pair of face

plates outward of the blocks, a resilient member interposed between each block and its face plate, and a pair of nut-equipped bolts extending through aligned holes in the blocks 5 and the face plates said holes being of such diameter as to permit free angular movement of said bolts therein.

2. The structure defined in claim 1 in which the heads and nuts of the bolts and the face 10 plates have ball and socket bearing surfaces.

3. A friction grip including a pair of laterally spaced blocks having cooperating half seats in their opposing faces, a pair of face 15 plates outward of the blocks, a resilient member interposed between each block and its face plate, a pair of nut-equipped bolts extending through aligned holes in the blocks and the face plates, and resilient means interposed between the blocks and held under compression 20 thereby.

4. A friction grip including a pair of laterally spaced blocks having cooperating half seats in their opposing faces, a pair of face 25 plates outward of the blocks, and a compressible rubber member interposed between each block and its face plate, and a pair of nut-equipped bolts extending through aligned holes in the blocks and the face plates.

5. A friction grip including a pair of laterally spaced blocks having cooperating half seats in their opposing faces, a pair of face 30 plates outward of the blocks, a resilient member interposed between each block and its face plate, a pair of nut-equipped bolts extending through aligned holes in the blocks and face 35 plates, and a piece of sponge rubber interposed between the blocks and held under compression thereby.

6. A friction grip including a pair of laterally spaced blocks having cooperating half seats in their opposing faces for a drill rod, a pair of nut-equipped bolts extending through aligned holes in the drill blocks and holding the blocks frictionally clamped onto 45 the drill rod, a face plate under the head of at least one of the bolts and adjacent block and an elastic rubber member interposed between said face plate and block, and resilient means interposed between the blocks and normally held compressed thereby.

In testimony whereof I affix my signature.
ALBERT HOSSFELD.
